UNITED STATES PATENT OFFICE.

RICHARD S. JACOBSEN, OF CHICAGO, ILLINOIS, ASSIGNOR, BY MESNE ASSIGNMENTS,
TO WEBSTER MFG. CO., A CORPORATION.

MEANS FOR OPERATING RECIPROCATING CONVEYERS OR SCREENS.

Application filed October 25, 1918. Serial No. 259,609.

This invention relates to a novel mechanism for driving conveyers or screens with a reciprocating motion wherein the forward and backward strokes of each revolution, respectively, progressively increase and diminish in speed for the greater part of their travel. This is, this progressive acceleration or retardation is applied to approximately two-thirds of the stroke, the last third being utilized in reversing and thereby reducing the shock which would occur in a sudden reversal.

The driving mechanism for imparting the desired motion to the conveying trough can be propelled by any source of power and is constructed and arranged for producing a progressively increasing and decreasing speed.

This particular motion is obtained and imparted to the conveying trough, through the employment of an eccentric disk, rotating about and guided by an eccentric sleeve, in such manner, that the distance from the center of said eccentric to the center of the drive shaft, is constantly and uniformly changing between the maximum and minimum.

To these and other purposes my invention consists in the novel construction, combination, provision and relative position of parts and members set forth in the following specification and accompanying drawings, and more particularly brought out in the claims.

Referring to the drawings in which like reference characters indicate like or corresponding parts, Figure 1 is an elevation showing a pair of troughs and my improved mechanism for imparting the herein described motion to the conveying troughs.

Figure 2 is a plan view of Figure 1.

Figure 3 is a section taken on line 3—3 of Figure 4, showing my improved driving means.

Figure 4 is a section taken on line 4—4 of Figure 3.

Figure 5 illustrates diagrammatically the motion and speed diagram of the troughs.

Referring to the drawing, I provide an eccentric sleeve bearing 10 which may be securely supported upon the concrete pier 11 or any suitable wood or steel support, by means of bolts 12 and which bearing is arranged to support the drive shaft 13 eccentrically with relation to the center line

14 of the sleeve bearing 10 whose extending sleeve ends 10^A are of slightly decreased diameter to fit the bore of the oppositely disposed hubs 15^A of the spaced eccentric disk walls 15^B which are connected by the arcuate annular wall 15^C to form an interior oil chamber 16 within the eccentric 15.

The hub end of the forked crank 17 is rigidly connected or keyed to the drive shaft 13 by means of key 18 and the ends of the two spaced arms 17^A are connected with the disk walls 15^B by means of link 19 and bolts or pins 20 and 21. The link 19 is made comparatively shorter than the crank arms 17^A and the pin 21 extends into walls 15^B. The pin 20 only connects the arms 17^A with link 19 and clears the inner face of walls 15^B.

The outer eccentric strap member of eccentric 15 is composed of two sections 15^D and 15^E securely bolted together with the bolts 22. An extending web 15^F and a pair of flanges 15^G afford a rigid connection for the connecting rod 23.

The distance between the center of the outside diameter of the eccentric sleeve end 10^A and the center of the eccentric disk 15^B is designated as "X" and the horizontal and vertical distances between the center of the outside diameter of the eccentric sleeve end 10^A and the center of the drive shaft 13 are designated by respective "Y" and "Z". The revolution of the drive shaft 13 will cause the eccentric disk 15^B to rotate about the center of drive shaft 13, through the keyed crank 17 and link 19, with a progressively increasing and decreasing speed.

The moment of the upper trough acting on the drive shaft is to a certain extent counter-acted by the moment of the lower trough acting on the same shaft, and the resulting moment which is transmitted to the supporting structure through sleeves 10 is equal to the difference of said moments.

Figures 1 and 2 illustrate a form of my invention as applied to stepped troughs arranged for horizontally conveying material in the same direction. Both upper and lower troughs are channel shaped and comprise sides 24^A and bottom 24^B. The troughs, as herein shown, are mounted for horizontal reciprocatory movement upon supporting rollers 25. A cross rod 26 mounted in the bearings 27 which are suitably and rigidly connected with the trough, cross-connects the outer ends of the rods 23. 110

2
A belt driven pulley 28 keyed to the drive shaft 13 imparts power thereto from any well-known source of power. A standard bearing is provided at 29 for the drive shaft 5 end.

Figure 5 represents the motion and speed diagram of the troughs. The speed increases approximately progressively from *a* to *b*, decreases quickly from *b* to *c*, increases 10 again from *c* to *d* in the same manner, and finally is retarded uniformly from *d* to *a*. According to Figure 5 this progressively 15 accelerated or retarded motion, respectively, takes place during about seventy-five per cent of each revolution and seventy per cent of the stroke. The other part of the motion serves for the reversal and ought not to be made smaller if the device is to be worked without injurious shock.

20 It will be observed that the speed of the forward and backward strokes of each revolution are reversedly identical and that the strokes progressively increase and diminish in speed for the greater part of their travel.

25 It is thought that the foregoing description and illustrations clearly disclose the construction and operation of the invention, hence a more extended explanation is omitted.

30 I claim:

1. Means for operating reciprocating conveyers or screens, comprising a uniformly rotating shaft; a drive pulley; a pair of bearings supporting said shaft eccentrically 35 thereto; an eccentric disk mounted on the bearings eccentric to the shaft; and means connected to said shaft between said bearings for driving said eccentric disk.

2. An eccentric driving mechanism for reciprocating conveyers or screens, comprising 40 a pair of stationary supporting elements, an eccentric disk arranged for rotary motion about said pair of stationary elements, said disk having a chamber therein; a shaft; and means within said chamber between said elements interconnecting said disk and said shaft.

3. An eccentric driving mechanism for reciprocating conveyers or screens, comprising 45 a pair of bearings; an eccentric disk mounted on said bearings, said disk having an oil chamber therein; a shaft arranged eccentrically to said bearings and passing through said chamber; and means within said chamber connected to said shaft for driving said eccentric.

4. Means for operating reciprocating conveyers or screens, comprising a uniformly 50 rotating shaft; a drive pulley; a pair of bearings supporting said shaft eccentrically thereto; an eccentric disk mounted on said bearings; a crank rigidly mounted on said shaft between said bearings; and a link connecting said disk and crank.

5. Means for operating reciprocating con-

veyers or screens comprising a pair of bearings; an eccentric disk mounted on said bearings, said disk having a chamber therein; a shaft mounted in said bearings; a crank within said chamber and rigid with 70 said shaft; and a link connecting said disk with said crank.

6. Means for operating reciprocating conveyers or screens comprising a pair of bearings; an eccentric disk mounted on said bearings, said disk having an oil chamber 75 therein; a shaft arranged eccentrically to said bearings and passing through said chamber; a crank within said chamber and rigid with said shaft; and a link connecting 80 said crank with said disk.

7. In a driving mechanism of the class described; a shaft; a pair of stationary bearings; said shaft passing through said bearings; an eccentric disk mounted for rotation 85 upon said bearings, said disk having a chamber therein; a crank arm within said chamber and rigid with said shaft; a link; a pin connecting said link with said crank arm, another pin connecting the other end of said 90 link with said disk; both of said pins being in double shear.

8. Means for operating reciprocating conveyers or screens; comprising a straight drive shaft; a plurality of pairs of symmetrically arranged bearings for supporting said shaft eccentrically to the adjacent ends thereof; eccentric disks mounted on the ends of said bearings; a chamber within each disk; crank arms rigidly connected to said drive shaft, and arranged within said chambers; a link connecting each crank arm with an eccentric disk; and connecting rods extending from said disks and pivotally supported at their other ends. 95

9. Means for operating reciprocating conveyers or screens comprising a drive shaft; a driving crank mounted on said drive shaft; a pair of eccentric bearings supporting said shaft; a power-transmitting eccentric disk arranged to rotate about said pair of eccentric bearings held in constant fixed relation to the axis of revolution of said driving crank, said crank being mounted within said disk; an operating member connected to said disk; means whereby said eccentric disk is connected with said crank to receive power therefrom for imparting to said operating member a progressively-accelerating motion in one direction with a reverse movement quick at first and progressively retarded in speed in the opposite direction, said acceleration and retardation being for the greater part of each stroke. 110

10. Means for operating reciprocating conveyers or screens, comprising a drive shaft; a plurality of bearings for supporting said shaft eccentrically to the adjacent ends of said bearings; eccentric disks mounted on the eccentric ends of said bear- 115 120 125 130

ings; cranks mounted within said disks and rigidly connected to said drive shaft; a link connecting each crank with an eccentric disk; and connecting means extending directly from said disks for imparting a reciprocating motion substantially as described.

11. Means for operating reciprocating conveyers or screens comprising a drive shaft; a plurality of bearings supporting said shaft eccentrically to the adjacent ends of said bearings; crank arms rigidly mounted on said shaft between said bearings; eccentric disks mounted on the ends of said bearings; and means attached to and within said disks arranged for actuation by said arms for operating the disks.

12. Means for operating reciprocating conveyers or screens, comprising in combination, a pair of bearings; an eccentric mounted on said bearings centrally between them; a uniformly rotating shaft extending through said bearings and eccentrically to the axis of revolution of said eccentric; and driving means for said eccentric arranged for connection to said shaft between said bearings.

13. Means for operating reciprocating conveyers or screens, comprising in combination, an eccentric having a divided hub and spaced, peripherally-connected, disk walls forming a chamber therebetween; a pair of bearings for said hub; a shaft extending between said bearings; and means operating within said chamber for operatively connecting said shaft and said eccentric.

14. Means for operating reciprocating

conveyers or screens, comprising in combination, an eccentric having a pair of oppositely disposed coaxial hubs and spaced, peripherally-connected, disk walls forming a chamber therebetween; a pair of bearings for said hub; a shaft extending between said bearings; and means operating within said chamber for operatively connecting said shaft and said eccentric.

15. Means for operating reciprocating conveyers or screens, comprising in combination, an eccentric having a pair of oppositely disposed coaxial hubs and spaced, peripherally-connected, disk walls forming a chamber therebetween; a pair of bearings for said hub; a shaft extending between said bearings; means operating within said chamber for operatively connecting said shaft and said eccentric, said means including a crank rigid on said shaft, a link, and a pair of pins connecting said link with said crank and said eccentric, said pins being in double shear.

16. Means for operating reciprocating conveyers or screens, comprising in combination, an eccentric having a divided hub and spaced, peripherally-connected, disk walls forming a chamber therebetween; a bearing for said hub; a shaft extending through said bearing and into said chamber; and means operating within said chamber for operatively connecting said shaft and said eccentric.

In witness whereof, I have hereunto subscribed my name this 22nd day of October, 1918.

RICHARD S. JACOBSEN.
